CLAIM

The ornamental design for a cosmetic packaging, as shown and described.

DESCRIPTION

FIG. 1 is a perspective view of a cosmetic packaging showing my new design;

FIG. 2 is a front view thereof;

FIG. 3 is a back view of thereof;

FIG. 4 is a right view thereof;

FIG. 5 is a left view thereof;

FIG. 6 is a top view thereof;

FIG. 7 is a bottom view thereof; and,

FIG. 8 is a front view thereof, wherein the cap is removed to show portions of the design not clearly visible when combined.

The broken lines in the figures illustrate portions of the article which form no part of the claimed design.
